UNITED STATES PATENT OFFICE

HEINRICH KUCKUCK, OF BREMEN, GERMANY

VENTILATOR

Application filed September 30, 1929, Serial No. 396,249, and in Germany January 17, 1929.

This invention relates to ventilators and has for an object provision of certain improvements in ventilating apparatus. More particularly the invention contemplates the provision of improved ventilating apparatus of the type used on ships by means of which better ventilation is accomplished by the manner in which air currents are guided around and through the apparatus.

The type of ventilator usually found on ships may be described as a sort of air funnel projecting upward from the ship's body and curved in a right angle at its upper open end. Ventilators of this type are generally turned against the wind. There are a number of disadvantages connected with ventilators of this type. The construction does not permit even, continuous ventilation, due to the fact that the air currents form whirls which prevent and obstruct uninterrupted air passage and consequently, reduce the efficiency of the equipment to a great extent. Various attempts were made in the past to overcome these and other difficulties. Ventilators have been constructed that employed the use of concave wind-shields or deflectors over the discharge opening in the ventilator. The part of the ventilator which is provided with the concave wind-shield is generally turned against the wind. The air current striking the concave wind-shield or deflector is deflected and consequently a sucking action is produced which draws out the air from the funnel connecting with the interior of the vessel. The resistance to the air travel is greatly increased by the formation of whirls and other gyrations that are set up in the air passages because the apparatus used has not been designed according to aerodynamic principles.

No ventilating device heretofore constructed has provided means of guiding and distributing the air current through the ventilator in such manner that the air currents are given stream-like motion.

The principal object of the invention is to produce a vigorous sucking action in the ventilator in order to withdraw foul air effectively from the interior of the vessel.

Another object consists in the provision of

means for reducing the resistance of the air currents approaching the ventilator.

Still another object is to provide a uniform distribution of the air currents within the ventilator to prevent gyration.

A further object has to do with means for adjusting the sucking action of the ventilator according to wind and weather conditions, and according to the speed of the vessel.

A further object resides in constructing a ventilator so that all sectional air currents escaping from the same altitude of the ventilated room, describe paths of equal length when passing through the ventilator to the outside.

Still another object is concerned with provision within the ventilator funnel for distributing and guiding the escaping air currents.

A further object relates to designing the ventilator in such a manner that sufficient suction is created within the interior of the ventilator even in case the wind should turn and transversely approach the ventilator.

Other objects relate to the provisions for readily changing the ventilator from the sucking type of ventilator to an air feeding type of ventilator. This provision permits use of the same ventilator for withdrawing foul air from the interior of a certain locality and for feeding fresh air into the same locality.

The invention will be better understood from a consideration of the following description in conjunction with the accompanying drawings, in which:

Fig. 1 is a vertical view partly in section of the apparatus in accordance with this invention, lines and arrows indicate air current travel;

Fig. 2, a side elevation showing another form in carrying out the invention;

Fig. 3, a plan view of apparatus shown in Fig. 2.

The apparatus illustrated in Fig. 1, shows the air funnel 1 adapted to be placed on the deck of a vessel and to be connected by means of a sleeve 2 to a tube (not shown) which leads to the interior of the vessel. To the funnel 1 is attached a horizontally disposed

ventilator cap 3, by means of a sleeve 4. The funnel 1 curves inside and to the rear of the ventilator cap 3, as shown, its end being designated by numeral 5. The end 5 of the funnel 5 is inclined, the dotted line W—V including an angle of about 45 degrees with the horizontal axis. Inside of the funnel 1 are distributing and guiding blades 6 placed transversely across the inside of the funnel 1, and 10 may be attached to opposite walls by spot welding. They follow the curving of the funnel and serve the purpose of uniformly guiding and distributing air currents and thereby prevent the formation of whirls 15 within the funnel. The blades are shaped in streamlines in such a manner as to provide the least resistance to the escaping air currents, and their shape and location within the funnel determines the proper guiding of the 20 air currents to impart streamline motion to the air currents.

Attached to the walls of the ventilator cap 3 are the spherically curved guiding and distributing air current reflectors designated by 25 numeral 7.

The distance between the line W—V and the reflectors and the end of the funnel should be not less than one third of the diameter of the funnel. The purpose of these 30 reflectors is to reflect the escaping air currents in streamlines to the outside, in uniform and even manner. The curvature and position of these reflectors with reference to the funnel 1 determines the distance the escaping air 35 currents have to travel to the outside.

The open end of the ventilator cap is curved slightly to the outside and provided with a rubber ring 8. This rubber ring is used when it is desired to close the ventilator 40 by means of the adjustable deflector 12. A closure may be desirable in case of bad weather; the adjusting may be prompted by wind conditions and by the speed of the vessel.

Attached to one side of the funnel 1, at 9, is a mounting which is provided with a thread 45 11 for adjustably receiving the deflector 12. A suitably shaped member 13, provided on the protruding center part of the deflector 12, 50 serves the purpose of adjusting the deflector with reference to the opening of the ventilator cap 3.

The adjusting may be desirable due to various conditions. The distance between the 55 outer margin of the deflector 12 and the rubber ring 8 of the ventilator cap may be increased or decreased and will for accordingly decreasing or increasing the sucking action. Should bad weather prevail, the deflector 60 may be used for entirely closing the ventilator cap.

The action of the ventilator described above in detail, will now be explained with reference to the air currents. Particular attention is called to the following features

which will readily be understood from a detailed explanation of the action which is to follow:

1. Least resistance to the onrushing air currents, due to the shape of the deflector 12; 70
2. Adjustability of sucking action;
3. Uniform distribution of the escaping air currents and prevention of whirls due to the provision of distributing and guiding blades 6, and due to the provision of the spherically curved air current reflectors 7;
4. General structure of the ventilator, whereby all sectional escaping air currents coming from the same altitude of the ventilated location, describe paths of equal length 80 through the ventilator to the outside.

The ventilator is located on the deck of a vessel and faces forward, i. e. the deflector 12 points in the travelling direction of the vessel. The dotted lines shown on the left of the drawings indicate the onrushing air currents which travel in the direction of the arrows from left to right. It will be evident, without elaborate description, that the peculiar shape of the deflector 12, being pointed in the center, sloping gradually down, and concave at the end, forces the onrushing air currents, as shown by the dotted lines, beyond and slightly above, but longitudinally to the ventilator cap 3. A vacuum is thereby tended to be created behind the deflector 12, the degree of which is determined, and the optimum of which may be adjusted, by the distance from the margin of the deflector 12 to the rubber ring 8 on the ventilator cap 3. 90

It may be mentioned at this point that the sucking action is dependent to a large extent on the shape of the deflector 12. An entirely concave deflector would, e. g. produce a still more vigorous vacuum and, therefore, sucking action. However, it may be remembered that such ventilators reach relatively enormous dimensions. The diameter of such a deflector as the one shown may run well over 12 feet in case of a large vessel. A strictly concave deflector would produce enormous resistance, which under certain circumstances would be felt detrimentally to the speed of the vessel. Numerous experiments have shown that the sucking action which is 105 reached with a deflector having concave margin is entirely sufficient under any and all circumstances. Its great advantage is that though the concave margin produces a strong vacuum yet the conical center part provides 110 for small resistance to the onrushing air.

The air currents, deflected by the deflector 12, as explained above, produce a vacuum which in turn causes a strong sucking action within the ventilator cap 3 and within 125 the funnel 1.

Referring now to the lower center part of the drawings in which full lines provided with arrows are shown pointing into the funnel 1, these lines designate the escaping 130

air currents rushing out from the ventilated locality, due to the sucking action created as explained above. When these air currents reach the upper curved part of the funnel 1, 5 they divide, due to the distributing and guiding blades 6, and are directed toward the arcuate air current reflectors 7. The shape of the guiding blades 6 which are formed in streamlines provides the least resistance to the 10 escaping air currents, guiding the air currents in streamlines and preventing gyration. When the air currents strike the reflectors 7, they are reflected and guided to the outside as 15 shown by the streamlines provided with arrows. Thus all irregular whirls within the ventilator are prevented and a path of equal distance is provided for all sectional escaping air currents which originated in the same 20 altitude of the ventilated locality.

20 An inspection of the drawings will show that the air currents, running up the left half of the funnel 1, have a relatively large distance to cover until they leave the funnel 1, and enter the interior of the ventilator cap 3, 25 while their path through the ventilator cap, to the outside, is relatively short. By examining Fig. 1, and particularly the streamlines on the right half of the funnel 1, which 30 designate the escaping air currents, it will be seen, that these air currents cover a relatively short distance within the funnel 1, but a correspondingly large distance within the ventilator cap 3. The distance these escaping air 35 currents have to travel through the ventilator is therefore approximately the same, regardless of the altitude of the ventilated locality in which they originate.

Fig. 1 represents merely the cross section 40 of the apparatus. Other views could be projected to indicate the fact that the shape of the funnel 1 is circular, and that this circular funnel is located within a circular ventilator cap. One must, therefore, in order to properly understand the streamline action of the 45 escaping air currents, visualize the picture shown in Fig. 1 in at least 3 projections. The streamlines as shown and described do not flow in a plane but within the cross-sectional area of the funnel and of the ventilator cap.

50 The description of the invention will now be continued with reference to the Figs. 2 and 3. These figures, as has been mentioned, represent a top side view and plan, respectively, of a ventilator having modified provisions for adjusting the deflector with reference to the ventilator cap opening, and having also provisions for changing the ventilator from an air sucking type to an air feeding type ventilator.

60 Only those parts of the modification shown in the Figs. 2 and 3 will be discussed in detail, which differ in structure or in purpose from the ventilator already described.

65 The guiding and distributing blades 6, shown in Fig. 2 are somewhat differently

shaped from the guiding blades 6 shown in Fig. 1. The latter are shaped not unlike streamline-shaped, with rounded lower part, slightly curved in accordance with the curvature of the funnel 1. Their streamline effect 70 will be obvious without further remarks. The shape of the blades in Fig. 2 are symmetrical as to their upper and lower part and the reason for this shape resides in the convertibility of the ventilator from a sucking type to an air feeding type ventilator. It is evident that in this case, the shape of the guiding and distributing blades must conform to the streamline action of the escaping 75 air currents, and must also conform to the streamline action of air currents fed into the ventilator cap 3 for the purpose of supplying fresh air to the interior of the locality with which the ventilator connects.

It will also be seen that the attachment of 80 the deflector 12 is different from the one shown in Fig. 1. While the latter was attached to the upper curved part of the funnel 1, inside of the cap 3, it is in the present case attached adjustably by means of brackets 14 and 15 which are fastened to the deflector 12, and which are attached to hinges on the carriers 16 and 17. These carriers are held in guide brackets 18 and 19, which are fastened to the sides of the ventilator cap 3. In the rear of the ventilator cap 3, the carriers unite in the part 20 which is provided with a threaded rotatable block 25 for taking the threaded adjusting screw 21. The threaded block 25 is turned by the geared worm 26 which is in turn rotated by the engaging worm wheel 27. Wheel 27 is connected to the shaft 28 which extends below the deck of the vessel and makes possible remote operation of the deflector 12. The shaft 28 may be turned manually as by the wheel 29 or mechanical or automatic means may be applied for this operation. Rotation of the block 25 causes the threaded screw 21 to be moved in and out in such manner that deflector 12 which is attached thereto is moved relatively to the cap opening for regulating the degree of desired suction.

105 A pin 22 is shown, fastened to a chain 23, which, in turn, is held by means of a bracket 24 on the outside of the ventilator cap 3. The deflector 12 may be removed from its mounting on the carriers 16 and 17, for the purpose of converting the ventilator from an air sucking to an air feeding type. In this case, the free opening of the ventilator cap 3, with the deflector removed, is turned in the travel direction of the vessel against the wind, and the wind will blow into the ventilator cap 3 110 and continue into the interior by way of the funnel 1, past the guiding and distributing blades 6. It will be clear that in this case, the reflectors 7 and the guiding and distributing blades 6 act again in the manner of 115 streamline guides in reversed direction.

The mounting of the removable deflector may, of course, be different from the one shown in these drawings. It may be preferable in certain cases, to mount the deflector so that it may be turned on hinges to the side, up or down, as desired, instead of entirely removing the same as shown. However, these are details of construction, which may readily be determined in some convenient fashion without departing from the spirit of the invention.

It is believed that the above account of the invention and its various features and objects will be sufficient for rendering an understanding of the invention and that the structure above shown is illustrative of the principle only and may be embodied in other forms without departing from the spirit or scope of the following claims.

20 I claim:

1. In a ventilating device, a ventilator cap open at one end, an air funnel projecting into the cap and terminating therein, the upper portion of the funnel being curved within the cap and toward the closed end thereof, a plurality of curved guiding and distributing blades disposed within the curved portion of the funnel for guiding and for distributing air currents in streamlines from the funnel into the cap, and reflecting means disposed within the cap for guiding and for distributing air currents in streamlines through the cap.

2. In a ventilating device, a ventilator cap open at one end, an air funnel projecting into the cap and terminating therein, the upper portion of the funnel being curved within the cap and toward the closed end thereof, a plurality of curved guiding and distributing blades disposed within the curved portion of the funnel for guiding and for distributing air currents in streamlines from the funnel into the cap, reflecting means disposed within the cap for guiding and for distributing air currents in streamlines through the cap, means on the open end of the cap and integral therewith for guiding air currents in streamlines out of the cap, and a streamline circular, concave deflector attached to the open end of the cap but separated therefrom for creating suction in the cap and in the funnel when an air current passes adjacent thereto.

3. In a ventilating device, a ventilator cap open at one end, an air funnel projecting into the cap and terminating therein, the upper portion of the funnel being curved within the cap and toward the closed end thereof, a plurality of curved guiding and distributing blades disposed within the curved portion of the funnel for guiding and for distributing air currents in streamlines from the funnel into the cap, reflecting means disposed within the cap for guiding and for distributing air currents in streamlines

through the cap, means on the open end of the cap and integral therewith for guiding air currents in streamlines out of the cap, and means attached to the cap and movable relatively thereto for creating suction in the cap and in the funnel when an air current passes adjacent thereto.

4. In a ventilating device, a ventilator cap open at one end, an air funnel projecting into the cap and terminating therein, the upper portion of the funnel being curved within the cap and toward the closed end thereof, a plurality of curved guiding and distributing blades disposed within the curved portion of the funnel for guiding and for distributing air currents in streamlines from the funnel into the cap, reflecting means disposed within the cap for guiding and for distributing air currents in streamlines through the cap, means on the open end of the cap and integral therewith for guiding air currents in streamlines out of the cap, a deflector attached to the cap and movable relatively thereto for creating suction in the cap and in the funnel when an air current passes adjacent thereto, and means for remotely controlling the movement of the deflector.

5. In a ventilating device, a ventilator cap open at one end, an air funnel projecting into the cap and terminating therein, the upper portion of the funnel being curved within the cap and toward the closed end thereof, a plurality of curved guiding and distributing blades disposed within the curved portion of the funnel for guiding and for distributing air currents in streamlines from the funnel into the cap, reflecting means disposed within the cap for guiding and for distributing air currents in streamlines through the cap, means on the open end of the cap and integral therewith for guiding air currents in streamlines out of the cap, a streamline air deflector located at the open end of the cap but separated therefrom and leaving an annular free passage for creating suction within the cap and within the funnel when an air current passes adjacent thereto, and a movable carrier disposed on the exterior of the cap for supporting the deflector.

6. In a ventilating device, a ventilator cap open at one end, an air funnel entering the cap and terminating therein, the upper portion of the funnel being curved within the cap and toward the closed end thereof, a plurality of curved guiding and distributing blades disposed within the curved portion of the funnel for guiding and for distributing an air current in streamlines from the funnel into the cap, reflecting means disposed within the cap for guiding and for distributing an air current in streamlines through the cap, means on the open end of the cap and integral therewith for guiding an air current in streamlines out of the cap, a streamline air deflector located at the open end of the

cap but separated therefrom and leaving an annular free passage for creating suction within the cap and within the funnel when an air current passes adjacent thereto, a 5 movable carrier disposed on the exterior of the cap for supporting the deflector, and remotely controlled means for moving the carrier to adjust the air deflector relative to the open end of the cap for regulating the 10 force of suction.

7. In a ventilating device, a ventilator cap open at one end, an air funnel projecting into and terminating therein, the upper portion of the funnel being curved within the cap and 15 toward the closed end thereof, a plurality of curved, streamlined blades disposed within the curved portion of the funnel for guiding and for distributing escaping air currents in streamlines into the cap and also adapted to 20 guide and to distribute incoming air currents in streamlines into the funnel, stationary air reflectors within the cap for guiding and for distributing escaping air currents in streamlines through the cap and also adapted for 25 guiding and for distributing incoming air currents in streamlines into the funnel, a movable and detachable streamlined air deflector disposed on the open end of the cap but separated therefrom and when attached adapted 30 to create suction in the cap and in the funnel and when detached permitting the entrance of air currents into the cap, a remote control attached to the deflector for moving said deflector relative to the cap opening for regulating 35 the amount of suction, and means attached to the open end of the cap for closing and for sealing the opening by means of the remotely controlled movable deflector.

8. In a ventilating device, a ventilator cap open at one end, an air-funnel projecting into the cap and terminating therein, the upper portion of the funnel being curved within the cap and toward the closed end thereof, and a deflector for creating suction in the cap and 40 in the funnel when an air current passes adjacent thereto disposed in front of the open end of the cap but spaced therefrom.

9. In a ventilating device, a ventilator cap open at one end, an air-funnel projecting into the cap and terminating therein, the upper portion of the funnel being curved within the cap and toward the closed end thereof, means within the cap disposed opposite the 45 open end of the curved funnel portion for guiding and distributing an air current in streamlines through the cap, and a deflector for creating suction in the cap and in the funnel when an air current passes adjacent thereto disposed in front of the open end of the cap but spaced therefrom.

10. In a ventilating device, a ventilator cap open at one end, an air-funnel projecting into the cap and terminating therein, the upper portion of the funnel being curved within the 50 cap and toward the closed end thereof, and a 55

deflector with a concave margin and a conical, projecting center disposed in front of the open end of the cap but spaced therefrom for creating suction in the cap and in the funnel when an air current passes adjacent thereto, 70 the said conical center projecting toward the said air currents.

11. In a ventilating device, a ventilator cap open at one end, an air-funnel projecting into the cap and terminating therein, the upper portion of the funnel being curved within the cap and toward the closed end thereof, and a deflector with a concave shaped margin, a convex inner surface and a conical projecting center, disposed in front of the open 75 end of the cap but spaced therefrom, for creating suction in the cap and in the funnel when an air current passes adjacent thereto.

12. In a ventilating device, a ventilator cap open at one end, an air-funnel projecting into the cap and terminating therein, the upper portion of the funnel being curved within the cap and toward the closed end thereof, a deflector disposed in front of the open end of the cap but spaced therefrom, for creating 80 suction in the cap and in the funnel when an air current passes adjacent thereto, and means for suitably varying the distance between the end of the cap and the deflector.

13. In a ventilating device, a ventilator cap open at one end, an air-funnel projecting into the cap and terminating therein, the upper portion of the funnel being curved within the cap and toward the closed end thereof, a deflector disposed in front of the open end of the cap but spaced therefrom for creating suction in the cap and in the funnel when an air current passes adjacent thereto, and means for suitably varying the distance between the 90 end of the cap and the deflector, 95

14. In a ventilating device, a ventilator cap open at one end, an air-funnel projecting into the cap and terminating therein, the upper portion of the funnel being curved within the cap and toward the closed end thereof, and a deflector disposed in front of the open end of the cap but spaced therefrom for creating suction in the cap and in the funnel when an air current passes adjacent thereto, and means for suitably varying the distance between the end of the cap and the deflector, said means 100 also forming a guide for guiding the deflector up against the margin of the cap to thereby shut the ventilating device off against the outer atmosphere.

15. In a ventilating device, a ventilator cap open at one end, an air-funnel projecting into the cap and terminating therein, the upper portion of the funnel being curved within the cap and toward the closed end thereof, and a movable and detachable air-deflector disposed in front of the open end of the cap for changing the device over from a suction type to a feeding type ventilator.

In testimony whereof I hereunto affix my 120 signature.

HEINRICH KUCKUCK.
